[57] CLAIM

The ornamental design for a seasoning dispenser housing, as shown and described.

DESCRIPTION

FIG. 1 is a side view of a first embodiment of a seasoning

dispenser housing for a pepper grinder showing our new design;

FIG. 2 is a top plan view of the first embodiment including a broken line illustration of part of the associated grinding mechanism;

FIG. 3 is a top plan view of the first embodiment with the grinding mechanism removed;

FIG. 4 is a bottom plan view of the first embodiment, again including a broken line illustration of part of the associated grinding mechanism;

FIG. 5 is a bottom plan view of the first embodiment with the grinding mechanism removed;

FIG. 6 is a side view of a second embodiment of a seasoning dispenser housing for a salt shaker showing our new design;

FIG. 7 is a top plan view of the second embodiment including a broken line illustration of the perforated dispensing cap;

FIG. 8 is a top plan view of the second embodiment with the dispensing cap removed;

FIG. 9 is a bottom plan view of the second embodiment including a broken line illustration of the closure plug; and,

FIG. 10 is a bottom plan view with the closure plug removed.

The broken lines portions of the Figures are for illustration purposes only and form no part of the claimed design.
